UNITED STATES PATENT OFFICE.

JOHN A. IRWIN, OF DETROIT, MICHIGAN, ASSIGNOR TO AMERICAN PRESSWELD RADIATOR CORPORATION, OF DETROIT, MICHIGAN, A CORPORATION OF MICHIGAN.

RADIATOR.

1,314,064.

Specification of Letters Patent. Patented Aug. 26, 1919.

Application filed January 14, 1918. Serial No. 211,733.

To all whom it may concern:

Be it known that I, JOHN A. IRWIN, a citizen of the United States, and residing at Detroit, in the county of Wayne and State 5 of Michigan, have invented a new and Improved Radiator, of which the following is a specification.

Some objection has been raised to the use of sheet metal radiators as heretofore constructed on the ground that rusting might take place in the water pockets which were formed at the lower ends of the sections. The object of the present invention is to overcome this objection and, incidentally, 15 to insure a more free circulation of air about the sections, whereby a greater radiation may take place per unit of radiating surface than is the case with ordinary constructions.

20 To this end, the invention consists in a radiator comprising a plurality of thin wide sheet metal sections nested together and having their extreme lower ends opening into a pipe which extends along beneath the sections, the sections and the pipe being connected by fused joints. It also consists in a radiator section formed of sheet metal halves welded together circumferentially, except at their lowermost points, where they 25 are spaced from each other and received in slots cut transversely in the upper wall of a connecting pipe. Again, the invention consists in a pair of thin wide pressed metal radiator sections having bosses near their 30 upper ends whereby they are spaced properly from one another, and being separated by an air space below the bosses throughout their entire length. The invention also consists in the details of construction shown, 35 described and claimed.

40 In the drawings, Figure 1 is an end view of a radiator showing a preferred embodiment of the invention. Fig. 2 is a fragmentary central longitudinal vertical section on a larger scale. Fig. 3 is an enlarged section on the line 3—3 of Fig. 2. Fig. 4 is a section on the line 4—4 of Fig. 1. Fig. 5 is a section on the line 5—5 of Fig. 4, showing the parts in larger scale than 45 does Fig. 2.

50 Each section is made up of the sheet metal halves 1 and 2 having the out-turned marginal flanges 3 and 4 welded together. At

their upper ends, the sections preferably include the bosses 5 and 6, whereby the proper 55 spacing is secured without the use of additional elements. If the particular radiator is intended for use with steam, it is unnecessary that there be any opening or connection between adjacent sections at the 60 top, but where it is designed for use with hot water, or on other two-pipe systems, any suitable connection may be employed. It is preferable also, as shown in Fig 3, to provide the halves of each section with telescopic 65 flanges 8 and 9 the edges of which are welded together to form stays. The sections may thus be made wide and thin to 70 secure a maximum radiating surface in a minimum space.

70 At the bottom of each section, the flanges 3 and 4 are spaced apart slightly and extended downwardly, as indicated at 10 and 11, to form narrow funnel-like passages 12 the longest dimensions of which are parallel to 75 the seams between the halves. These down-turned flanges are received in slots which are cut transversely in a pipe 13 preferably arranged in the central longitudinal plane of the radiator. The connections between 80 the pipe and the sections are made by welding. Since the pipe is usually of thicker material than the sections, it would be difficult, if not impossible, were no provision 85 made to avoid it, to secure a proper fusion of the joint. For this purpose, the outer portion of the pipe is cut away around the slots, as shown at 15, to a thickness substantially that of the metal of the section. Upon directing the flame of a blow pipe into 90 the notch, fusion of the pipe and the section takes place simultaneously. It is desirable to fill in the notch somewhat with additional molten metal 16 in order to properly 95 strengthen the parts.

The sections may be clamped tightly together at the top, if desired, by the bolts 18 that pass through the openings formed by the flanges 8 and 9 and extend from end to end of the radiator.

100 It will be noted that the sections are spaced apart from each other at all points below the bosses 5 and 6: a more rapid circulation of air is thus allowed than can take place in ordinary radiators, which results in 105 increased radiation per unit of surface,

By threading the pipe 13 at each end (but one end being shown) the radiator may readily be connected to existing pipes regardless of whether they are at the right or 5 the left of the proposed location. The other end of the pipe is, of course, closed by a cap 19. The chief advantage of this pipe 13 is that it affords means for draining the radiator and thus obviating the undesirable 10 effect of water standing in the bottom of the sections which may cause rusting. Any water which may stand in the comparatively heavy pipe 13 will have no more effect there than anywhere else in the entire heating 15 system.

It is evident that the details of construction may be varied to a considerable extent without departing from the spirit of the 20 invention and I do not, therefore, wish to be limited except as indicated by the subjoined claims.

I claim:—

1. A sheet metal radiator comprising a wide thin section including a pair of side 25 portions having circumferential flanges secured together, there being an opening between the side portions at the lowermost point in the section, and a tubular member of less diameter than the transverse width 30 of the section connected to the section around the opening through which all water of condensation is allowed to escape.

2. A radiator comprising a tubular member notched in its upper side, a sheet metal 35 radiator section having a downwardly convex and perforated lower end received in the notch and connected to the walls thereof.

3. A radiator comprising a tubular member notched transversely in its upper side, a 40 thin wide sheet metal radiator section including a pair of sides joined to each other along their margins except at their lowest points where they are spaced apart to form an opening which registers with the notch,

the sides being welded to the walls of the 45 notch in the tubular member.

4. A radiator comprising a plurality of thin wide sheet metal sections, each having an opening in its lower end at substantially its lowermost point, and a tubular member of less diameter than the width of the section and provided with notches into which said openings lead, said member being arranged substantially perpendicular to the planes of the sections and being secured to 55 the sections around the openings.

5. A radiator comprising a plurality of thin wide sheet metal sections each having an opening in its wall at substantially the lowest point, a tubular member having 60 transverse notches in which those portions of the sections immediately surrounding the openings are received, the metal of the sections being fused with that of the tubular member at the notches. 65

6. A radiator comprising a thin wide section formed of two halves of thin sheet metal joined along their margins, a notched tubular metal member formed of thicker material than the section, the tubular member having its outer portion removed for a short distance around the notch to render the material at the notch of approximately 70 the same thickness as the metal of the section, the section being welded to the tubular 75 member around the notch.

7. A radiator comprising a plurality of upright thin sheet metal sections nested together, a tubular member notched to receive the lower edges of the sections, the metal of 80 the sections projecting into the notches to form spout like elements through which all water may flow from the section into the member, the walls of the notches being welded to the section above the lower ends 85 of the spout-like elements.

JOHN A. IRWIN.
